BURGLAR ALARM

Wan Kwong Yip, Kowloon, Hong Kong, assignor to
Chung AH Manufacturing Company Limited, San Po
Kong, Kowloon, Hong Kong

Filed Dec. 20, 1971, Ser. No. 210,309

Claims priority, application Great Britain Oct. 13, 1971

Term of patent 14 years

Int. Cl. D29—99; D8—07
U.S. Cl. D72—1 A

FIG. 1

FIG. 2

FIG. 1 is a perspective view of a burglar alarm showing my new design.

FIG. 2 is an elevational view of the side opposite that shown in FIG. 1.

The side of the burglar alarm as seen from the left of FIG. 2 is flat and unornamented.

I claim:

The ornamental design for a burglar alarm, substantially as shown and described.
